CLAIM

The ornamental design for a wet/dry vacuum cleaner,
as shown and described.

DESCRIPTION

FIG. 1 is a front perspective view of a wet/dry vacuum
cleaner showing our new design;

FIG. 2 is a right side elevational view thereof, the left
side being a mirror image except for the cord exit;

FIG. 3 is a front elevational view thereof;

FIG. 4 is a rear elevational view thereof;

FIG. 5 is a top plan view thereof; and

FIG. 6 is a bottom plan view thereof.

The electrical cord has been shown fragmentarily in
FIGS. 2, 4, 5 and 6 for ease of illustration.

The cart shown in broken lines in FIG. 1 is for illustrative
purposes only and forms no part of the claimed
design.
